SHEET HOLDER

Bruce K. Slonberger, Dayton, Ohio

Application January 5, 1949, Serial No. 69,389

17 Claims. (Cl. 282—29)

1

This invention relates to a sheet holder adapted to receive a plurality, or pile, of superposed individually removable sheets, such as sales slips or the like. The present invention is a further development of the type of sheet holder shown in the pending applications of Bruce K. Slonberger and Clifford S. Slonberger, Serial Number 681,012, filed July 2, 1946, and of Bruce K. Slonberger, Serial Number 49,569, filed September 16, 1948, and Serial Number 57,845, filed November 2, 1948.

One object of the invention is to provide a sheet holder of a simple, efficient construction which can be produced at a relatively low cost.

A further object of the invention is to provide such a structure with a sheet supporting member which, when the closure is moved to its open position, will move automatically to a position to permit used sheets, or carbon copies, to be inserted in the holder below the sheet supporting member.

A further object of the invention is to provide such a sheet holder with sheet retaining means which will prevent the relative displacement of the sheets in all positions to which the sheet supporting member may be moved and from which the uppermost sheet can be quickly and easily withdrawn.

A further object of the invention is to provide means for supporting a resilient sheet supporting member on the end wall of the holder and preventing the vertical movement thereof.

A further object of the invention is to provide a sheet holder with simple, easily operated means for releasing the closure for complete removal from the holder.

A further object of the invention is to provide a sheet holder which can be used with equal facility in connection with a pile of unconnected sheets or with a pad of sheets the end portions of which are attached one to the other, such as a sales book.

Other objects of the invention may appear as the device is described in detail.

In the accompanying drawings Fig. 1 is a top plan view of a sheet holder embodying the invention, partly broken away; Fig. 2 is a longitudinal sectional view taken through such a holder; Fig. 3 is a side elevation of the holder with the closure in its open position; Fig. 4 is a rear end elevation of the holder of Fig. 1; Fig. 5 is a section taken through one end of the holder showing a sales book mounted therein; Fig. 6 is a similar view showing a pile of unconnected sheets supported in the holder; Fig. 7 is a top

5 plan view of a slightly modified form of the front end portion of the holder; Fig. 8 is a top plan view of a modification of the invention with the closure in its open position and partly broken away; Fig. 9 is a sectional view taken through the bottom member and the sheet supporting member of the holder of Fig. 8 and showing the top member in elevation and partly broken away; Fig. 10 is a section taken on the line 10—10 of Fig. 8; Fig. 11 is a side elevation of a front end portion of the holder with the closure in its closed position; and Fig. 12 is a side elevation of a part of the holder showing the connection between the top member and the bottom member.

15 In these drawings I have illustrated two embodiments of my invention and have shown the same as particularly adapted for use with sales slips or sale books, but it is to be understood that the holder may take various forms and may be used with sheets of various kinds, the word 20 "sheet" being herein used to include either a one piece sheet or a multiple sheet unit comprising upper and lower parts which may be detached one from the other.

25 In that embodiment shown in Figs. 1 to 7 the holder comprises a bottom member, a top member movably supported on the bottom member and a sheet supporting member which is supported between the top and bottom members and arranged to divide the space between said members into an upper compartment to receive and support unused sheets and a lower compartment to receive and store used sheets, or copies. In the particular arrangement shown the bottom member comprises a shallow receptacle having a bottom wall 20, side walls 21, a front end wall 22 and a rear end wall 23. The receptacle is 30 preferably formed from a single sheet of metal drawn or otherwise formed to the desired shape. The end and side walls are in the present instance of substantially the same height. The top member constitutes a movable closure for the receptacle and preferably comprises a flat sheet 24 slidably supported on the side walls 21 of the receptacle, as by providing the closure with in-turned edge portions 25 forming guideways which 35 embrace and are slidable on outturned flanges 26 at the upper edges of the side walls. In the present instance it is provided at its rear end 40 with a downwardly extending, curved end wall 27.

The sheet supporting member which is interposed between the bottom wall of the receptacle and the top member, or closure, is adapted to receive and support a pile of superposed sheets and 45 that end portion of the supporting structure ad- 55

jacent the front wall 22 is biased upwardly but is held normally in its depressed position by the closure 24. When the closure is retracted, or moved to its open position, the upwardly biased portion of the supporting member moves upwardly out of the receptacle. The supporting member may take various forms. Preferably it comprises a sheet 28 of resilient material the rear end of which is held against vertical movement and the forward portion of which is biased upwardly. In the arrangement here shown the rear end of the supporting structure 28 is mounted directly upon the rear end wall 23 of the receptacle. For that purpose the rear end portion of the sheet is bent upwardly and then downwardly to form a U-shaped structure 29 adapted to receive the upper portion of the end wall 23 and to fit snugly about the same, thus holding the rear end of the supporting member against movement. The forward portion of the supporting member is inclined upwardly and forwardly and is biased in an upward direction. At its forward end the supporting member is provided with an inwardly or rearwardly extending member which overhangs the forward end portion of the pile of sheets 30a on the supporting member. In the arrangement shown the forward end portion of the supporting member is bent upwardly as shown at 30 and then rearwardly to provide a lip 31 which is spaced vertically from the adjacent portion of the supporting member. In the present instance there is mounted on the lip 31 a U-shaped element 32 the purpose of which will hereinafter appear, and this U-shaped element forms a part of the overhanging member which serves to limit the upward movement of the forward end portion of the pile of sheets.

For the purpose of moving the end portion of the pile of sheets toward the overhanging member and holding the same against displacement there is mounted on the sheet supporting member a sheet retaining device having an upwardly biased part arranged below and engaging the end portion of the pile of sheets. In the arrangement here shown this retaining device comprises a sheet of resilient material 33 preferably of a length and breadth somewhat less than the length and breadth of the supporting member, and the rear portion of the retaining member is rigidly secured to the sheet supporting member, preferably approximately midway between the ends thereof, as by spot welding as shown at 34. The retaining member extends forwardly and upwardly from its line of connection with the supporting member, with its forward end below the overhanging member or lip, and this forward portion is biased upwardly and engages the end portion of the pile of sheets with sufficient pressure to firmly grip the same and prevent the accidental displacement of the sheets, but to permit the sheets to be individually withdrawn. However, it is preferable to provide means for positively preventing the longitudinal displacement of the sheets, and for this purpose a bar 60 is secured to an intermediate part of the supporting member and has at its rear end an upwardly extending part 61 to engage the rear end of the pile of sheets. It will be understood that when the U-shaped element 32 is not used the lip 31 alone constitutes the overhanging member with which the retaining member cooperates, such an arrangement being shown in Fig. 9.

As has been stated, the upwardly biased portion of the sheet supporting structure is retained in its depressed position by the top closure 24.

When the closure is in its forward, or fully closed, position the forward end thereof may extend either below or above the overhanging member, 31-32, and when the closure extends below the overhanging member the end portion of the pile of sheets is pressed against the lower surface of the closure, as shown in Fig. 2. When the closure is moved from its closed position to its open position the free or main portion of the uppermost sheet of the pile of sheets may be separated from the next lower sheet and elevated above the level of the closure to permit the latter to be moved forwardly beneath the same and thus provide a writing support for the sheet. Usually a sales slip comprises two parts and a transfer medium is interposed between the two parts so that the record written on the upper part will also appear on the lower part. In some instances the transfer medium is applied to the lower surface of the upper part of the sheet but in other instances it is desirable to employ a separate transfer medium, or carbon sheet, and the purpose of the U-shaped member 32 is to provide means for attaching the end portion of the carbon sheet to the sheet supporting member so that it may be inserted between two parts of each sheet unit as the units are successively withdrawn from the receptacle for use. To attach the carbon sheet to the supporting member the U-shaped member is removed from the lip 31, the end of the carbon sheet is inserted between the two parts of the U-shaped member and folded about the rear edge of the lower part thereof and the U-shaped member then replaced on the lip 31, thus causing the inserted portion of the carbon sheet to be gripped firmly between the U-shaped member and the lip and to extend forwardly in line with the lower surface of the overhanging member. Normally when the holder is not in use the carbon sheet will be within the receptacle above the pile of sheets and below the closure. When the closure is moved to its open position the carbon sheet and the free portion of the uppermost sheet of the pile are withdrawn, the closure then moved forwardly into supporting relation to the withdrawn sheet, and the carbon sheet inserted between the upper and lower parts of the sheet. The end portion of the closure is moved beneath the overhanging member 31-32 and between the end portions of the withdrawn sheet and the next lower sheet and the carbon sheet extends forwardly in a straight line and is free from bend or buckle. When the entry has been made on the withdrawn sheet the latter is removed as a whole from the retaining devices and the end portion of the withdrawn sheet having no contact with the next lower sheet the removal thereof has no tendency to displace the lower sheet. The closure is then moved to its open position, thereby releasing the upwardly biased end portion of the sheet supporting member for movement to a position above and spaced from the front end wall of the receptacle, as shown in Fig. 3, and the lower part or copy of the record sheet is detached and inserted through the space between the elevated end of the sheet supporting member and the front end wall of the receptacle into the latter.

It is desirable that the closure shall be completely removable from the receptacle but it is also desirable that means should be provided to prevent the accidental complete removal of the closure. In the present instance the closure is provided adjacent its lower forward end with one or more downwardly extending projections 35, such as small depressions, which form stops. The

vertical length of these projections is such that they may move over the upper edge of the rear end wall and over the U-shaped part 29 of the sheet supporting structure, the latter being spaced slightly below the lower surface of the closure. Mounted on the rear end wall of the receptacle, and in the present instance on the U-shaped structure 29, are two U-shaped clips 36 the upper ends of which are in contact with or are very close to the lower surface of the closure and these clips are movable lengthwise of the end wall 23 into and out of positions in the line of movement of the projections 35. When the clips are in the line of movement of the projections the outward movement of the closure is interrupted before it is completely withdrawn. When the clips are moved out of line with the projections the latter can move over the U-shaped structure 29, thus permitting the closure to be completely withdrawn.

In Fig. 7 I have shown the upper wall of the U-shaped member 32, which is carried by the sheet supporting member, as provided with a longitudinal slot 37 of such size that a name card or the like inserted between the upper wall 25 of the member 32 and the lip 31 can be read through the slot.

In Figs. 8 to 12 there is shown a modified construction in which the invention is embodied in a hinged holder of the type shown in application Serial Number 681,012, above mentioned. As shown in these figures the bottom member comprises a receptacle having a bottom wall 40, an upwardly curved forward end wall 41 and side walls 42 of a height substantially less than the height of the front wall. The sheet supporting member 43 is pivotally connected at its rear end with the rear end of the bottom wall 40 of the receptacle and as here shown the sheet supporting member is provided at its rear end with a downwardly turned intermediate portion 43a the lower edge portion of which is rolled to form a hinge member 44. The bottom wall of the receptacle is provided at each side of the hinged member 44 with extensions which are rolled to form hinge members 45, a hinge pin 46 extending through the several hinge members. The downturned portion 43a of the supporting member supports the rear end of the latter in spaced relation to the bottom wall 40 and the forward portion of the supporting member is biased upwardly as shown in Fig. 9, the supporting member being preferably formed of resilient sheet metal. At its forward end the supporting member is provided with an upwardly extending part 47 the upper portion of which is bent rearwardly to form a lip 48 which overhangs the end portion of a pile of sheets 49 on the supporting member. As here shown the overhanging member 48 is in direct contact with the top surface of the pile of sheets but if desired it could be provided with a member for attaching a carbon sheet thereto, as shown at 32 in Fig. 2. A resilient sheet retaining member 50 is secured at its rear end to the sheet supporting member 43 and the forward portion thereof is inclined and biased upwardly with its forward end below the lip 48 to grip the end portions of the sheets between the same and the lip.

The top member comprises a top wall 51, a downwardly curved rear end wall 52 and downwardly extending side walls 53 which extend downwardly below the upper edges of the side walls 42 of the receptacle and on the inner sides of the side walls 42. The lower edge portions 75 of the side walls 53 are offset inwardly to pro-

vide upwardly facing shoulders 54 which have sliding and supporting engagement with the lateral edge portions of the sheet supporting member 43. The forward portions of the side walls 53 extend downwardly, as shown at 55, to form shoulders which engage the hinge pin 46 and limit the outward or opening movement of the closure. The forward ends of the side walls 53 are curved, as shown at 56, to conform to the curvature of the front wall 41 of the receptacle and when the closure is in its foremost or closing position these rounded ends 56 of the side walls 53 extend into the curved end wall 41 and thus hold the receptacle against downward movement with relation to the sheet supporting member and closure. In this position the closure retains the forward portion of the sheet supporting member in its depressed position and the forward end of the top plate 51 of the closure may extend either above or below the lip 48. When the closure is moved rearwardly to its open position the forward portion of the sheet supporting member is released for upward movement and the receptacle is released for downward movement with relation to the sheet supporting member. However, in practice the receptacle is usually supported in one hand of the operator and the sheet supporting member and the closure are moved about the axis 46 with relation thereto. With the closure in its open position the free or main portion of the uppermost sheet of the pile of sheets may be withdrawn and the closure is then moved forwardly beneath the withdrawn sheet to form a support therefor, the forward end of the top wall 51 extending beneath the lip 48 and between the forward end portions of the uppermost sheet and the next lower sheet of the pile, and the curved end portions of the closure extending into the end wall 41 of the receptacle to retain the several parts in fixed relative positions while an entry is being made upon the withdrawn sheet. When the entry has been made the withdrawn sheet is removed from the pile and the top plate 51 being between the two upper sheets the removal of the uppermost sheet has no tendency to displace the next lower sheet. However, it is preferable to provide the sheet supporting member at its rear end with an upwardly extending stop member 57 to hold the sheets at all times against relative longitudinal displacement. The withdrawn sheet, or a copy thereof, if a copy is made, is inserted in the receptacle, the latter being preferably provided with an upwardly biased finger 58 which retains the sheets in the receptacle when the latter is in its open position. The receptacle and the closure are then moved into substantial alinement and the closure moved forwardly to depress the forward portion of the sheet supporting structure and to engage the rounded ends of the side walls of the closure with the end wall 41 of the receptacle to again secure the several parts in their closed positions.

While I have shown and described two embodiments of my invention I wish it to be understood that I do not desire to be limited to the details thereof as various modifications may occur to a person skilled in the art.

Having now fully described my invention what I claim as new and desire to secure by Letters Patent is:

1. A sheet holder comprising a bottom member, a top member connected with said bottom member for movement with relation thereto, a sheet supporting member supported between and

spaced from said bottom member and said top member, one end portion of said supporting member being biased upwardly and being normally held by said top member against upward movement, a part carried by said biased end portion of said supporting member and spaced above the same, a sheet retaining device carried by said supporting member and having an upwardly biased part beneath the first mentioned part to engage the end portion of a pile of sheets on said supporting member and retain the same between said parts.

2. A sheet holder comprising a bottom member, a top member connected with said bottom member for movement with relation thereto, a sheet supporting member supported between and spaced from said bottom member and said top member, one end portion of said supporting member being biased upwardly, a part carried by said end portion and spaced above the same, a sheet retaining device carried by said end portion and having an upwardly biased part beneath the first mentioned part to engage the end portion of a pile of sheets on said supporting member and retain the same between said parts, said top member being movable to a position above the first mentioned part to retain the biased end portion of said supporting member in its lowermost position.

3. A sheet holder comprising a bottom member, a top member connected with said bottom member for movement with relation thereto, a resilient sheet supporting member between and spaced from said top and bottom members, one end of said supporting member being held against vertical movement and the other end portion thereof being biased upwardly, a member carried by and spaced from said upwardly biased end portion of said supporting member to engage the end portion of a pile of sheets on said supporting member, and a resilient sheet engaging member secured to said supporting member between the ends of the latter and inclined upwardly toward the first mentioned sheet engaging member with its free end below the latter to engage said end portion of said pile of sheets and retain the same between said sheet engaging members.

4. A sheet holder comprising a bottom member, a top member connected with said bottom member for movement with relation thereto, a resilient sheet supporting member between and spaced from said top and bottom members, one end of said supporting member being held against vertical movement and the other end portion thereof being biased upwardly, a member carried by and spaced from said upwardly biased end portion of said supporting member to engage the end portion of a pile of sheets on said supporting member, and a resilient sheet engaging member secured to said supporting member between the ends of the latter and inclined upwardly toward the first mentioned sheet engaging member with its free end below the latter to engage said end portion of said pile of sheets and retain the same between said sheet engaging members, said top member being movable to a position to retain said biased end portion of said supporting member in a depressed position and to a position to release said end portion for upward movement.

5. A sheet holder comprising a receptacle having a bottom wall, side walls and a front end wall, a sheet supporting member extending for substantially the full length of said receptacle above said bottom wall, the forward portion of

said supporting member being biased upwardly and having adjacent said front end wall an upwardly extending part provided with an inwardly extending lip, a sheet retaining member secured to said supporting member and having a movable part below said lip and biased toward the same to grip the end portion of a pile of sheets on said supporting member, and a top closure for said receptacle normally holding said biased end portion of said supporting member against upward movement and movable to a position to permit said end portion of said supporting member to move to a position above said end wall.

6. A sheet holder comprising a receptacle having a bottom wall, side walls and a front end wall, a sheet supporting member extending for substantially the full length of said receptacle above said bottom wall, the forward portion of said supporting member being biased upwardly and having adjacent said front end wall an upwardly extending part provided with an inwardly extending lip, a sheet retaining member secured to said supporting member and having a movable part below said lip and biased toward the same to grip the end portion of a pile of sheets on said supporting member, and a top closure for said receptacle normally holding said biased end portion of said supporting member against upward movement, said closure being movable to a position to permit the free portion of the uppermost sheet of said pile of sheets to be elevated above the next lower sheet, and being then movable to a supporting position below said uppermost sheet and with its forward end between the forward end portions of said uppermost sheet and the next lower sheet.

7. A sheet holder comprising a bottom member, a top member connected with said bottom member for movement with relation thereto, a sheet supporting member supported between and spaced from said bottom member and said top member, one end portion of said supporting member being biased upwardly and being normally held by said top member against upward movement, a part carried by said end portion of said supporting member and spaced above the same, a sheet retaining device carried by said supporting member and having an upwardly biased part beneath the first mentioned part to engage the end portion of a pile of sheets on said supporting member and retain the same between said parts, said top member being movable to a position to release the biased end portion of said supporting member for upward movement and to permit the free portion of the uppermost sheet of said pile of sheets to be separated from the next lower sheet and being then movable to supporting relation to said separated sheet with its forward end between the forward end portions of said separated sheet and said next lower sheet and to depress said biased end portion of said supporting member and retain the same in said depressed position.

8. A sheet holder comprising a receptacle having a bottom wall, side walls, and front and rear end walls, a top closure movably supported on said receptacle, a resilient sheet supporting member having at its rear end an upwardly extending part U-shaped in cross section to receive the upper edge portion of said rear end wall and support said sheet supporting member in said receptacle, the forward portion of said sheet supporting member being biased upwardly and having at its forward end an upwardly extending

part provided at the upper edge thereof with an inwardly extending member, a resilient sheet retaining member secured adjacent its rear end to said sheet supporting member, the forward portion of said retaining member being biased upwardly and having its forward end below said inwardly extending member, the forward portion of said sheet supporting member being held against upward movement by said closure when the latter is in receptacle closing position.

9. A sheet holder comprising a receptacle having a bottom wall, side walls, and front and rear end walls, a top closure movably supported on said receptacle, a resilient sheet supporting member having at its rear end an upwardly extending part U-shaped in cross section to receive the upper edge portion of said rear end wall and support said sheet supporting member in said receptacle, the forward portion of said sheet supporting member being biased upwardly and having at its forward end an upwardly extending part provided at the upper edge thereof with an inwardly extending member, a resilient sheet retaining member secured adjacent its rear end to said sheet supporting member, the forward portion of said retaining member being biased upwardly and having its forward end below said inwardly extending member, the forward portion of said sheet supporting member being held against upward movement by said closure when the latter is in receptacle closing position, and a U-shaped member supported on and embracing said inwardly extending part and adapted to receive the end portion of a transfer sheet and secure the latter to said inwardly extending part.

10. A sheet holder comprising a bottom member, a top member connected with said bottom member for movement with relation thereto, a sheet supporting member supported between said top and bottom members, one end portion of said supporting member being biased upwardly, a part extending upwardly from said end portion and having a lip extending forwardly therefrom above and spaced from said end portion, a sheet retaining device carried by said supporting member and having an upwardly biased part beneath said lip to engage the end portion of a pile of sheets on said supporting member, and a device supported on said lip and having a part extending beneath the latter to grip the end portion of a transfer sheet between the same and said lip.

11. A sheet holder comprising a bottom member, a top member connected with said bottom member for movement with relation thereto, a sheet supporting member supported between said top and bottom members, one end portion of said supporting member being biased upwardly, a member carried by said supporting member above and spaced from said end portion thereof, a sheet retaining member carried by said supporting member and having an upwardly biased part beneath the last mentioned member to engage the end portion of a pile of sheets on said supporting member, and a U-shaped device supported on the last mentioned member and adapted to receive the end portion of a transfer sheet and secure the latter to said last mentioned member.

12. A sheet holder comprising a receptacle having a bottom wall, side walls, and front and rear end walls, a top closure movably supported on said receptacle, a resilient sheet supporting member having at its rear end an upwardly extending part U-shaped in cross section to receive the upper edge portion of said rear end

wall and support said sheet supporting member in said receptacle, the forward portion of said sheet supporting member being biased upwardly and having at its forward end an upwardly extending part provided at the upper edge thereof with an inwardly extending member, and a resilient sheet retaining member secured adjacent its rear end to said sheet supporting member, the forward portion of said retaining member being biased upwardly and having its forward end below said inwardly extending member, the forward portion of said sheet supporting member being held against upward movement by said closure when the latter is in receptacle closing position.

13. A sheet holder comprising a receptacle having a bottom wall, side walls, and front and rear end walls, a top closure movably supported on said receptacle for movement across said rear end wall, means for supporting a pile of sheets in said receptacle, said top closure having adjacent the front end thereof a downwardly extending projection of such vertical length that it may move over said rear end wall, and a member supported on the upper portion of said rear end wall for movement lengthwise of the latter into and out of the path of said projection.

14. A sheet holder comprising a receptacle having a bottom wall, side walls, and front and rear end walls, a top closure movably supported on said receptacle, a sheet supporting member having at its rear end an upwardly extending part U-shaped in cross section to receive the upper edge portion of said rear end wall and support said sheet supporting member in said receptacle, said closure having adjacent its front end a downwardly extending projection which is movable over said U-shaped part of said supporting member, and a member mounted on said U-shaped part and movable into and out of the path of said downwardly extending projection.

15. A sheet holder comprising a bottom member, a member supported above said bottom member to support a pile of sheets, one end portion of said member being movable toward and from said bottom member and being normally held against movement from said bottom member, a part carried by said movable end portion of said supporting member and overhanging said end portion to limit the upward movement of the pile of sheets thereon, and means carried by said supporting member to yieldably press the end portion of said pile of sheets against said overhanging part and retain the same normally against movement with relation one to the other while permitting the uppermost sheet of said pile to be withdrawn therefrom.

16. A sheet holder comprising a bottom member, a sheet supporting member above said bottom member having one end thereof pivotally connected with the adjacent end of said bottom member, the other end portion of said supporting member being biased upwardly and having a part rigid therewith and extending inwardly above the same in spaced relation thereto, a sheet retaining device mounted on said supporting member and having a part below said inwardly extending part and biased toward the latter, and a top member slidably connected with said supporting member for movement to and from a position above said biased end portion of the latter.

17. A sheet holder comprising a bottom member, a resilient sheet supporting member pivotally connected one end with the adjacent end

of said bottom member and having its free end portion inclined upwardly, a part rigid with and extending upwardly from the free end of said inclined portion and having at its upper edge a lip extending above the adjacent portion of said supporting member, a resilient sheet retaining member secured at one end to said supporting member and having its free end portion inclined upwardly and biased toward said lip, and a top member having side walls slidably connected with said supporting member for movement in a direction to depress said inclined portion of

said supporting member and retain the same in its depressed position.
